UNITED STATES PATENT OFFICE.

JOSEPH ST. ANTOINE, OF CHEBOYGAN, MICHIGAN.

WRECK-INDICATOR.

No. 882,974.

Specification of Letters Patent. Patented March 24, 1908.

Application filed September 7, 1906. Serial No. 333,717.

To all whom it may concern:

Be it known that I, JOSEPH ST. ANTOINE, a citizen of United States, residing at Cheboygan, in the county of Cheboygan and State 5 of Michigan, have invented certain new and useful Improvements in Wreck-Indicators; and I do hereby declare the following to be a full, clear, and exact description of the invention, such as will enable others skilled in the 10 art to which it appertains to make and use the same.

This invention relates to improvements in apparatus for marking sunken vessels and has for its object to provide a device of that 15 nature adapted to be bolted to the deck of a vessel occupying but little space thereon and carrying a buoy adapted to be lifted and floated off as the vessel sinks, the buoy carrying a signal and having a cable connection 20 with the stationary part of the apparatus.

With the above and other ends in view the invention consists in the construction, combination and arrangement of parts all as hereinafter fully described, specifically claimed 25 and illustrated in the accompanying drawings in which—

Figure 1 is a side elevation of the invention. Fig. 2 is a vertical section. Fig. 3 is a top view with the chest open.

Like parts are designated by corresponding reference numerals in the several views.

Referring more particularly to the drawings 7 designates a chest bolted or otherwise secured to the deck of the vessel by means of 35 the securing ears 1, and provided with a lid or cover 8 held by the hinges 2, and in which is formed a slot 9 communicating with the interior of the chest, this lid being normally closed by means of the lock 3.

Located within the chest is a reel 10 mounted upon the standards 11 which are secured above by means of the cross-rods 4. These standards revolvably support the shaft 5, having the crank 5' as shown. Secured to 45 the shaft 5, is the reel or drum 10.

Located upon the upper face of the chest lid at opposite sides thereof is a pair of supporting brackets 13 the lower ends of which have the securing ears 14 for fastening the 50 brackets to the cover. The upper end of each bracket is bent upon itself to form a saddle 15 within which the mast 16 normally rests.

The mast has a square shoulder forming 55 portion 16' against which a barrel shaped buoy 17 preferably made of sheet metal is

secured by means of an ear 6. In addition one end of the mast is provided with a visible signal 18 while its opposite end carries a metallic strap 19 in which is swivelly mounted an I-bolt 20 to which one end of the cable 21 is secured, the opposite end of the cable being fastened to the reel 10. As shown in Fig. 2, this cable is guided between the cross-rods 4. The cable is further provided with a weight 22 secured thereto adjacent the strap 19, the weight tending to raise the mast into vertical position as the vessel sinks and the mast is floated from its brackets.

In the operation of the device the mast will be floated from its supports by means of its buoy as the vessel sinks, the weight carried by the mast forcing the same into upright position, the cable unwinding from the reel, 75 until the vessel finally settles.

When not in use the mast is carried by the brackets, as shown in Fig. 2, the entire device occupying but little space upon the deck.

The cable is provided with graduations or 80 scale markings a foot apart from each other and numbered from the reel end of the cable, so that when the cable has been completely unwound an approximate estimate of the depth at which the wreck lies is obtainable. 85

Having thus described my said invention, what I claim as new is—

In the device of the character described, the combination with a slotted lid-provided chest, of standards mounted within said 90 chest, cross-rods securing the upper ends of said standards, a shaft revolvably supported by said standards, a reel upon said shaft, a scale marked cable secured at one side to said reel, an I-bolt secured to the remaining 95 end of said cable, a swivel secured to said I-bolt, a mast having a shoulder forming portion, said swivel being secured to said shoulder forming portion, a barrel shaped buoy upon said mast and stopped by said 100 shoulder forming portion, said cable passing between said cross-rods, and a weight secured to said cable near said mast.

In testimony whereof, I affix my signature in presence of two witnesses.

JOSEPH ^{his} ST. ANTOINE.
